HEIGHT GAGE

James L. Taylor, 12319 Woodruff Ave.,
Downey, Calif. 90024

Filed Nov. 20, 1972, Ser. No. 308,052

Term of patent 14 years

Int. Cl. D10—04

U.S. Cl. D52—6 R

FIG. 1 is a front elevational view of a height gage showing my new design, the rear of the read-out gage being plain;

FIG. 2 is a right side elevational view thereof;

FIG. 3 is a top plan view thereof; and

FIG. 4 is a left side elevational view thereof with the read-out gage having been omitted for ease of illustration.

I claim:

The ornamental design for a height gage, substantially as shown and described.
